180,400

ELECTROMAGNETIC UNIT

Hugh J. Hall, Los Altos, Ralph W. Kane, Atherton, and
Emery H. Rogers, Palo Alto, Calif., assignors to Varian
Associates, San Carlos, Calif., a corporation of California

Application January 24, 1955, Serial No. 34,185

Term of patent 14 years

(Cl. D26—1)

FIG. 1

FIG. 2

Fig. 1 is a front perspective view of an electromagnetic unit showing our new design;

Fig. 2 is a view in front elevation, and

Fig. 3 is a view in side elevation.

The rear and side, not shown, are like the respective front and side shown.

We claim:

The ornamental design for an electromagnetic unit, as shown and described.
